PILGER ROLLING MILL

Richard Ludwig, Dusseldorf-Unterrath,
GermanyApplication January 25, 1930, Serial No. 423,449
In Germany February 7, 1929

20 Claims. (CL. 80—14)

This invention is for improvements in or relating to a process and apparatus for the production of tubes upon a Pilger rolling mill.

In the rolling out of tubes in accordance with the Pilger process, mandrels are used which are not cylindrical, but are shaped with a slight taper so that the same, after the rolling out of a tube, may be more easily withdrawn from the tube.

This taper of the Pilger mandrel has, however, the disadvantage, that when the Pilger rolls are maintained at a constant distance from one another, a tube rolled thereby is cylindrical outside and tapered inside, so that the thickness of the wall at the end of the tube where the rolling process commences is greater than at the end thereof where the said process finishes. In order to obtain an equal thickness of the wall over the whole length of the tube, it is necessary, during the rolling of the tube, to control the distance which separates the two Pilger rolls in a manner which compensates for the taper of the mandrel. This has hitherto been effected directly by the operator through the medium of the normal roll adjusting apparatus.

As the displacement of the rolls by independent adjustments as above described must only amount to a few hundredths of a millimeter, the manipulation of the regulating device of the adjusting apparatus necessitates great skill and attention on the part of the operator. The separate adjustments of the rolls to regulate the distance apart thereof are generally too great or too small, so that tubes are produced having walls of marked irregular thickness.

The present invention comprises a process for the production of tubes having a constant wall thickness upon Pilger rolling mills, characterized by the feed apparatus of the mill being operatively connected to the Pilger rolls by means whereby the two Pilger rolls are automatically moved relatively to one another during the rolling of a tube by an amount corresponding to the taper of the mandrel. The transmission of the movement of the feed apparatus to the Pilger rolls can be effected in any suitable manner.

In order that the invention may be fully understood reference is directed to the accompanying drawings in which:—

Figure 1 is a sectional side elevation of a Pilger rolling mill constructed in accordance with this invention.

Figure 2 is a sectional plan of Figure 1.

Figure 3 is a view similar to Figure 1 of a modified form of Pilger rolling mill constructed in accordance with this invention.

Figure 4 is a plan of Figure 3.

Figure 5 is a vertical transverse section of a further modified form of Pilger rolling mill constructed in accordance with this invention.

Figure 6 is a sectional side elevation of the mill illustrated in Figure 5, and

Figure 7 is a plane of Figure 6.

Referring to Figures 1 and 2 of the drawings, 1, 1 indicate the frame of a rolling mill with Pilger rolls 2, 2 mounted therein in the usual manner and the upper roll of which can be raised or lowered by means of the screwed spindles 3, worm wheels 4, worms 5 keyed upon a shaft 11 which may be driven from a source of power, as for example, an electric motor 6. A Pilger mandrel 7 is arranged to carry a hollow bloom 8 which is to be rolled out, and a driving rod 9 is provided for imparting a feed movement to the mandrel 7 and bloom 8 from a driving apparatus 10 in the usual manner.

The free end of the shaft 11 is extended and is arranged to carry one element 12 of a cone clutch which, during the rolling process of the tube is arranged to be frictionally coupled to the other element 16 of the clutch by means of a fork 13 engaging therewith and which is connected to a lever 14 and a weight 15. A key 17 provided upon the shaft 11, and a corresponding keyway in the clutch element 12 engaging therewith, permits the latter to be axially displaced along the shaft 11 but ensures that the said element and shaft rotate together. The disengagement of the two clutch elements 12 and 16 is accomplished by lifting the weight 15 through the medium of a cord 18 or any other suitable apparatus. The clutch element 16 is firmly connected by a hollow shaft 19 to a worm wheel 20 and is rotatably carried in a bearing 21. A worm 22 is arranged in engagement with the worm wheel 20 and is mounted in fixed relation upon a shaft 23 provided with screw thread of relatively large pitch.

A correspondingly screw threaded nut 25 is mounted upon the screw threaded shaft 23 and upon the rolling operation of the tube, is arranged to be displaced along the steeply inclined thread of the shaft 23 in the direction of the arrow Figure 2, by means of an arm 26 secured to the feed driving apparatus 10. A pin 27 mounted upon the arm 26 is arranged to engage between adjacent teeth 24 provided upon the nut 25 and thereby prevents the rotation of the latter.

The method of operation of the apparatus is as follows:

The clutch elements 12 and 16 are first disen-

gaged by lifting the weight 15, the rolls are then adjusted by means of the worms 5 to the normal smallest outside diameter of the tube to be rolled. The weight 15 is thereupon dropped and the worm shaft 11 is coupled to the worm wheel 20. The feed driving apparatus 10, with the Pilger mandrel 7 and the hollow bloom 8 supported thereon is then moved towards the roll frame 1 so that the free end of the Pilger mandrel is disposed between the rolls, the arm 26 on the driving apparatus 10 abuts against the nut 25 on the screw threaded spindle 23 and the pin 27 engages between two teeth 24 of the nut and prevents the rotation thereof.

15 As the process of rolling the tube proceeds the accompanying displacement of the nut 25 along the spindle 23 causes the latter to be rotated. This rotation is transmitted by the worm 22, worm wheel 20, hollow spindle 19, clutch elements 12 and 16, key 17, worm shaft 11, worms 5 and worm wheels 4, to the press spindles 3, which raise the upper Pilger roll 2 proportionally to the feed movement of the apparatus 10 and by an amount corresponding to the taper of the Pilger mandrel.

20 As the described operation of raising the upper roll is distributed uniformly over the whole length of the mandrel, the thickness of the wall of the rolled tube is exactly the same throughout, as compared with the irregular thickness of wall having stepped graduations which is obtained by the previously known processes.

25 A similar arrangement to that shown in Figures 1 and 2 is illustrated in Figures 3 and 4, in which the lower Pilger roll 2 is automatically raised and lowered while the upper Pilger roll is maintained in a predetermined position.

30 As in Figures 1 and 2, a Pilger roll frame is provided with a feed driving device as usually arranged and the numerals 1 to 10 indicate similar parts of the apparatus to those indicated in Figures 1 and 2. A wedge 30 is arranged below each of the two bearings of the lower Pilger roll 2 and is arranged to be displaced by the rotation of a screw threaded spindle 31 engaging therewith.

35 The spindles 31 are connected by means of pairs of bevel wheels 32 and spindles 33 and 34 with a roller 35 mounted upon the latter. One or more spiral grooves 36 are formed in the roller 35, and one end of an arm 37 secured to the driving apparatus 10 is arranged in engagement with the said groove 36.

40 With this arrangement, the upper roll is adjusted to the normal diameter of the tube to be rolled in the manner previously described with reference to Figures 1 and 2. When the feed device 10 has moved the mandrel and hollow bloom to a position where the free end of the mandrel is disposed between the Pilger rolls, the arm 37 engages with and slides along the spiral groove 36 of the roller 35 and thereby rotates the said roller at a relatively slow speed.

45 This rotating movement is transmitted through the spindles 33 and 34, and bevel wheels 32, to the screw threaded spindles 31, which displace the wedges 30 beneath the bearings of the lower Pilger rolls 2, so that the roll gradually falls as the tube is rolled by an amount corresponding to the taper of the Pilger mandrel.

50 When a tube has been rolled, a return movement of the feed driving apparatus 10, causes the roller 35 to be rotated in the reverse direction to that above described by the arm 37 into its initial position and the two wedges 30 together

5 with the lower Pilger roll are also brought into the initial position thereof.

55 In Figures 5, 6 and 7, a form of construction is shown in which, as in Figures 3 and 4, a roller 35 is employed provided with a spiral groove 36 and into which latter an arm 37' secured to the feeding apparatus 10 is arranged to extend. The rotation of the roller 35 by the arm 37' as the rolling operation proceeds, is transmitted by a spindle 38 to a worm drive 39-40 and to toothed wheels 41, 42 and 43. The wheels 42 are mounted upon hollow internally and externally screwed sleeve nuts 44 arranged to screw into the frames 1. The internal screw threads of the nuts 44 are arranged in engagement with the corresponding externally screwed spindles 3 and it will be observed that the rotation of the spindle 38 during the rolling of a tube, causes the upper Pilger roll to be raised, in a manner similar to that described with reference to Figures 1 and 2, by an amount corresponding to the taper of the Pilger mandrel.

15 I claim:—

20 1. A Pilger rolling mill which comprises in combination a tapered mandrel arranged to support a tubular bloom co-axially thereon, rolls carried by the mill, means for feeding said mandrel and bloom between at least one pair of rolls, a nut and at least one feed screw operable by the rotation of the nut to move one of a pair of 25 said rolls relatively to the other, and means connecting said nut and said feeding means to move the said roll during a rolling operation by an amount corresponding to the taper of the mandrel.

30 2. A Pilger rolling mill which comprises in combination a tapered mandrel arranged to support a tubular bloom co-axially thereon, rolls carried by the mill, means for feeding said mandrel and bloom between at least one pair of said 35 rolls, a nut and at least one feed screw operable by the rotation of the nut to move one of a pair of said rolls relatively to the other, and a clutch mechanism between said nut and said feeding means, means connecting said clutch mechanism 40 to said feeding means and means connecting said clutch mechanism and said nut, whereby to move the said roll during a rolling operation by an amount corresponding to the taper of the mandrel.

35 3. A Pilger rolling mill which comprises in combination a tapered mandrel arranged to support a tubular bloom co-axially thereon, rolls carried by the mill, means for feeding said mandrel and bloom between at least one pair of said 45 rolls, a rotatable screw threaded spindle having a thread of relatively large pitch, a nut arranged in engagement therewith and adapted to be moved by the feeding means so as to rotate the said spindle, and means operated by said spindle 50 to move the rolls relatively to one another during the rolling operation.

40 4. A Pilger rolling mill which comprises in combination a tapered mandrel arranged to support a tubular bloom co-axially thereon, rolls 55 carried by the mill, means for feeding said mandrel and bloom between at least one pair of said rolls, a rotatable screw threaded spindle having a thread of relatively large pitch, a nut arranged in engagement with said spindle and adapted to 60 be moved by the feeding means so as to rotate the said spindle, and means operated by said spindle to move the rolls relatively to one another during the rolling operation and clutch mechanism between said roll-moving means and said 65 70

75 75

- spindle for temporarily disabling said roll-moving means.
5. A Pilger rolling mill which comprises in combination a tapered mandrel arranged to support a tubular bloom co-axially thereon, rolls carried by the mill, means for feeding said mandrel and bloom between at least one pair of said rolls, at least one feed screw operable to move one of a pair of said rolls relatively to the other, 10 and an operative connection between said feed screw and the said feeding means to move the said roll during a rolling operation by an amount corresponding to the taper of the mandrel, the said operative connection including a rotatable screw threaded spindle having a thread of relatively large pitch and a nut arranged in engagement therewith and adapted to be moved by the said feeding means so as to rotate the said spindle.
- 15 6. A Pilger rolling mill which comprises in combination a tapered mandrel arranged to support a tubular bloom co-axially thereon, rolls carried by the mill, means for feeding said mandrel and bloom between at least one pair of said rolls, at least one feed screw operable to move one of a pair of said rolls relatively to the other, and an operative connection between said feed screw 10 and the said feeding means to move the said roll during a rolling operation by an amount corresponding to the taper of the mandrel, the said operative connection including a rotatable screw threaded spindle having a thread of relatively 15 large pitch and a nut arranged in engagement therewith and adapted to be moved by the feeding means so as to rotate the said spindle, the said feeding means being provided with a stop member arranged to engage automatically during a rolling operation with a projection provided upon the said nut so as to prevent the rotation thereof.
- 20 7. A Pilger rolling mill which comprises in combination a tapered mandrel arranged to support a tubular bloom co-axially thereon, rolls carried by the mill, means for feeding said mandrel and bloom between at least one pair of said rolls, and an operative connection between said feeding means and at least one of the said rolls for automatically moving the rolls relatively to one 25 another during a rolling operation by an amount corresponding to the taper of the mandrel, the said operative connection including a rotatable screw threaded spindle having a thread of relatively large pitch and a nut arranged in engagement therewith and adapted to be engaged and moved by the said feeding means so as to rotate the said spindle, the said feeding means being provided with a stop member arranged to engage automatically during a rolling operation with a projection provided upon the said nut so as to prevent the rotation thereof.
- 30 8. A Pilger rolling mill which comprises in combination a tapered mandrel arranged to support a tubular bloom co-axially thereon, rolls carried by the mill, means for feeding said mandrel and bloom between at least one pair of said rolls, and an operative connection between said feeding means and at least one of the said rolls for automatically moving the rolls relatively to one 35 another during a rolling operation by an amount corresponding to the taper of the mandrel, the said operative connection including a clutch mechanism and a rotatable screw threaded spindle having a thread of relatively large pitch and a nut arranged in engagement with said spindle and adapted to be moved by the feeding means so as to rotate the spindle, the said feeding means being provided with a stop member arranged to engage automatically during a rolling operation with a projection provided upon the said nut so as to prevent the rotation thereof.
- 40 9. A Pilger rolling mill which comprises in combination a tapered mandrel arranged to support a tubular bloom co-axially thereon, rolls carried by the mill, means for feeding said mandrel and bloom between at least one pair of said rolls, at least one feed screw operable to move one of a pair of said rolls relatively to the other, 40 and an operative connection between said feed screw and the said feeding means to move the said roll during a rolling operation by an amount corresponding to the taper of the mandrel, the said operative connection including a 45 clutch mechanism and a rotatable screw threaded spindle having a thread of relatively large pitch and a nut arranged in engagement with said spindle and adapted to be moved by the feeding means so as to rotate the spindle, the said feeding means being provided with a stop member arranged to engage automatically during a rolling operation with a projection provided upon the said nut so as to prevent the rotation thereof.
- 45 10. A Pilger rolling mill which comprises in combination a tapered mandrel arranged to support a tubular bloom co-axially thereon, rolls carried by the mill, means for feeding said mandrel and bloom between at least one pair of said rolls, at least one feed screw operable to move one of a pair of said rolls relatively to the other, 50 and an operative connection between said feed screw and the said feeding means to move the said roll during a rolling operation by an amount corresponding to the taper of the mandrel, the said operative connection including a 55 clutch mechanism and a rotatable screw threaded spindle having a thread of relatively large pitch and a nut arranged in engagement with said spindle and adapted to be moved by the feeding means so as to rotate the spindle, the said feeding means being provided with a stop member arranged to engage automatically during a rolling operation with a projection provided upon the said nut so as to prevent the rotation thereof.
- 50 11. A Pilger rolling mill which comprises in combination, a tapered mandrel adapted to support a tubular bloom co-axially thereon, rolls carried by said mill, means for feeding said mandrel and bloom between at least one pair of said rolls, 50 a screw threaded spindle of relatively large pitch, an operative connection between said feeding means and said spindle, means operatively connected to at least one of said rolls for automatically moving the rolls relatively to one another 55 by an amount corresponding to the taper of the mandrel, said operatively connected means being driven by said spindle during a rolling operation.
- 55 12. A Pilger rolling mill which comprises in combination, a tapered mandrel, adapted to support a tubular bloom co-axially thereon, rolls carried by said mill, means for feeding said mandrel and bloom between at least one pair of said rolls, a screw threaded spindle of relatively large 60 pitch, an operative connection between said feeding means and said spindle, clutch mechanism connected to at least one of said rolls for automatically moving the rolls relatively to one another by an amount corresponding to the taper of the mandrel, said clutch mechanism being driven by said spindle during a rolling operation.
- 60 13. A Pilger rolling mill which comprises in combination, a tapered mandrel arranged to support a tubular bloom co-axially thereon, rolls 65
- 70
- 75

- carried by said mill, means for feeding said mandrel and bloom between at least one pair of said rolls, at least one feed screw operable to move one of a pair of said rolls relatively to the other, 5 a screw threaded spindle of relatively large pitch adapted to be rotated during a rolling operation, an operative connection between said feed screw and said screw threaded spindle, means arranged to engage the thread on said spindle and to be moved by said feeding means to operate said feed screw and cause relative and automatic movement between said rolls by an amount corresponding to the taper of the mandrel.
14. A Pilger rolling mill which comprises in combination, a tapered mandrel arranged to support a tubular bloom co-axially thereon, rolls carried by said mill, means for feeding said mandrel and bloom between at least one pair of said rolls, at least one feed screw operable to move one of a pair of said rolls relatively to the other, a screw threaded spindle of relatively large pitch adapted to be rotated during a rolling operation, clutch mechanism between said feed screw and said screw threaded spindle, means arranged to engage the thread on said spindle and to be moved by said feeding means to operate said feed screw and cause relative and automatic movement between said rolls by an amount corresponding to the taper of the mandrel.
15. A Pilger rolling mill which comprises, in combination, a tapered mandrel arranged to support a tubular bloom co-axially thereon, rolls carried by the mill, means for feeding said mandrel and bloom between at least one pair of rolls, a nut and at least one feed screw operable on the rotation of said nut to move one of a pair of said rolls relatively to the other, a screw threaded spindle of relatively large pitch adapted to be rotated during a rolling operation, an operative connection between said nut and screw threaded spindle, and means arranged to engage a thread on said spindle and to be moved by said feeding means to operate said feed screw and cause a relative and automatic movement between the said rolls by an amount corresponding to the taper of the mandrel.
16. A Pilger rolling mill which comprises, in combination, a tapered mandrel arranged to support a tubular bloom co-axially thereon, rolls carried by the mill, means for feeding said mandrel and bloom between at least one pair of rolls, a nut and at least one feed screw operable on the rotation of said nut to move one of a pair of said rolls relatively to the other, a screw threaded spindle of relatively large pitch adapted to be rotated during a rolling operation, clutch mechanism between said nut and screw threaded spindle, and means arranged to engage a thread on said spindle and to be moved by said feeding means to op-

erate said feed screw and cause a relative and automatic movement between the said rolls by an amount corresponding to the taper of the mandrel.

17. A Pilger rolling mill comprising a tapered mandrel arranged to support a tubular bloom coaxially thereon, rolls carried by the mill, means to feed said mandrel and bloom between said rolls, clutch mechanism between said feeding means and at least one of said rolls, means connecting said clutch mechanism with said feeding means, and means for taking the motion which said clutch mechanism derives from said feeding means and moving the rolls relatively to one another during the rolling operation by an amount corresponding to the taper of the mandrel.

18. A Pilger rolling mill comprising a tapered mandrel arranged to support a tubular bloom coaxially thereon, rolls carried by the mill, means to feed said mandrel and bloom between said rolls, a feed screw operative to move at least one of said pair of rolls, and means connecting said feeding means to said feed screw for automatically moving the rolls relatively to one another during a rolling operation by an amount corresponding to the taper of the mandrel, said connecting means operating during the forward movement of the tube while the tube is not under the influence of the rolls.

19. A Pilger rolling mill comprising a tapered mandrel arranged to support a tubular bloom coaxially thereon, rolls carried by the mill, means to feed said mandrel and bloom between said rolls, clutch mechanism between said feeding means and at least one of said rolls, means connecting said clutch mechanism with said feeding means and means including a feed screw for taking the motion which said clutch mechanism derives from said feeding means and moving the rolls relatively to one another during the rolling operation by an amount corresponding to the taper of the mandrel.

20. A Pilger rolling mill which comprises in combination a tapered mandrel arranged to support a tubular bloom coaxially thereon, segmental Pilger rolls carried by the mill, means to move the mandrel forward and backward between the rolls, a limited extent on a working and return stroke, means operating predeterminedly to give a greater throw to said forward stroke to progress said mandrel and tube through said rolls and to successive treatments thereby, means for adjusting one of said rolls with respect to the other, and means for positively connecting said mandrel, progressing means to said roll adjusting means to automatically change the roll pass in an amount corresponding to the progressing taper of the mandrel.

RICHARD LUDWIG.
